UNITED STATES PATENT OFFICE.

JACOB W. KING, OF GALESBURG, ILLINOIS, ASSIGNOR, BY DIRECT AND MESNE ASSIGNMENTS, TO ALBERT J. PERRY, TRUSTEE, OF GALESBURG, ILLINOIS.

PIPE-WRENCH.

SPECIFICATION forming part of Letters Patent No. 788,156, dated April 25, 1905.

Application filed October 25, 1904. Serial No. 229,944.

To all whom it may concern:

Be it known that I, JACOB W. KING, a citizen of the United States, residing at Galesburg, in the county of Knox and State of Illinois, 5 have invented certain new and useful Improvements in Pipe-Wrenches, of which the following is a specification, reference being had thereto to the accompanying drawings.

Figure 1 is a view, partly in longitudinal section and partly in elevation, of a wrench embodying my improvements. Fig. 2 is a side elevation of the jaws and parts adjacent thereto. Fig. 3 is a cross-section of the shank, taken on the line $\alpha\alpha$, Fig. 2, showing the 15 movable jaw in plan. Fig. 4 is a side view of the movable jaw detached. Fig. 5 is a side view of the carrier in which the movable jaw is hinged. Fig. 6 is a vertical section on the line $\gamma\gamma$ of Fig. 2.

20 In the drawings the shank or stem of the tool is indicated by 1, it having a head at 2 capable of serving as a hammer and provided with a lateral extension 4, serving as the fixed jaw of the wrench, this part having the grip-ping-teeth at 5.

25 3 is the handle part, which may be of any preferred character.

The sliding jaw is carried by an adjustable head 6, which projects outward with a taper, 30 as shown at 7, it having two guiding and bracing loops 8 and 9, which surround the stem. It is socketed at 10, the wall of the socket being threaded and fitted to a threaded adjusting-bolt 11, having the thumb-head 12, by 35 which it can be rotated in the usual way, the end of the bolt abutting against a projecting shoulder at 13. The bearing-surface of this head 6 is inclined downward and outward relatively to the stem and to the line of the teeth 40 5 on the stationary head. Grooves are cut at 6^a 6^b in the part 6, these providing a guide-way for the carrier of the movable jaw. The body part or block of the movable jaw-piece is indicated by 14. At the side it is recessed, 45 as shown at 14^a, and at the bottom it is cut away, as shown at 14^b, leaving the rib or projection 14^c. This jaw is mounted in a sheet-metal strap-loop 15 17, it being secured thereto by a hinge at 16. The side parts of the strap-

loop fit in the rabbets 14^a. The loop proper 50 is indicated by 17 and surrounds the stem 1, it being capable of slipping along the latter longitudinally and also of being moved with the jaw-block toward and from the stem.

The body part is secured in position in the 55 strap-loop by means of a screw or screws, as shown at 20. Parts 14 and 15 are normally held in their outermost positions by means of a spring 21, interposed between the part 14 and the stem. The spring is preferably placed 60 in a socket 23, formed in the part 14 and arranged to bear against a sliding pin 22, which in turn bears against the stem or shank 1 of the tool. The jaw and the parts attached thereto can be rocked around the hinge at 16 65 whenever it is desired to obtain access to the parts covered by it.

The strap-loop 15 has its lower edges turned in to form guide-tongues 25, which fit the 70 grooves 6^a in the head 6.

The sliding jaw-block 14 rests upon a series of antifriction-rollers 24, which are interposed between the block 14 and the head 6. They are prevented from escaping in one direction 75 by the rib 14^c of the block 14 and in the other direction by a holder on the part 6, preferably a plate 26, secured by the screw 27.

If at any time it is desired to obtain access to the covered surfaces or to the rollers, it is merely necessary to loosen the screw at 20, 80 when the whole block can be turned outward on the hinge at 16.

The shank part 1 of the tool is not uniform in cross-section from end to end; but at lines near its outer end it widens or is made gradually thicker on the side opposite to the sliding jaw 14, as is shown at 28. The loop part 17 of the sliding strap 15 17 is adapted to slide along the edge or face of this tapered part 28 and to be held thereby in different positions 85 in relation to the stem. For example, if by means of the screw 11 12 the head 6 is adjusted so as to have the jaw 14 comparatively close to the stationary jaw 4 the loop 17 will be gradually moved backward in relation to 90 the shank and the sliding jaw will be held correspondingly nearer to the shank on the opposite side. Consequently the jaw 14 will 95

reciprocate over a shorter path. Hence when the tool is being used for turning relatively small bodies the sliding jaw is automatically adjusted or set to such position that it will move back and forth distances proportional to the size of the objects which it engages.

The manner of using a tool having my improvements will be readily understood. If, for example, a pipe or like object is to be rotated, the head 6 is first adjusted to proper distance from the head 4. The parts are then put into position for gripping the pipe, and if the wrench be rotated by the handle 3 a powerful and increasing bite is caused, the block 14, with its teeth 19, tending to move toward the stem 1 under the pressure that is being applied. As soon as the turning stress ceases the spring 21 forces the block outward to its normal position.

20 When a pipe, bolt, nut, or other object of relatively large diameter is to be operated on, the head 6 and the sliding jaw 14 are by the screw 11 set at a proportionately long distance from the jaw 4 and at each swinging 25 movement of the tool the travel of the jaw 14 will be long in proportion to the size of the object; but, vice versa, when a pipe or other body of short diameter is to be engaged the head 6 and jaw 14 are adjusted to points near 30 the jaw 4, and during such adjustment the tapered part 28 of the stem will gradually move the strap-loop 15 17 and the jaw 14 inward toward the shank and hold the jaw 14 against prolonged reciprocations, and they will be 35 short and rapid in proportion to the said diameter of the engaged body.

I am aware of the fact that various forms have heretofore been proposed of wrenches of this class, each having a fixed jaw and an adjustable 40 head moving along the stem of the fixed jaw, together with a spring-held jaw-plate. I am also aware of the fact that antifriction-rollers have been proposed for use in pipe-wrenches. These rollers are subjected to great strain and pressure, and access is frequently necessary to the 45 interior parts in order to maintain them in working order, and I believe myself to be the first to have devised a construction and arrangement of parts which permits the operation 50 to quickly and readily attain the ends desired with a tool of this sort, and I believe myself also to be the first to provide a tool of this class having a jaw which is movable back and forth during each swinging reciprocation 55 of the tool and which has its parts so constructed that the travel of the jaw will be regulated and stopped, so as to be proportional to the diameter of the object being gripped.

60 What I claim is—

1. In a pipe-wrench, the combination with the stem 1 having a fixed head 2 with the teeth 5, of the adjustable head 6, the strap-loop surrounding the stem 1 and slidably mounted on

the head 6, the jaw-block 14 hinged at 16 in 65 the strap-loop, the antifriction-rollers between the jaw-block and the head, means for fastening the jaw-block 14 against rotation on the hinge, and the spring interposed between the stem 1 and the jaw-block, substantially as set 70 forth.

2. In a wrench, the combination of the stem 1 with the fixed head 2 having the teeth 5, the sliding head 6, the bolt 11 for adjusting the head along the stem 1, the antifriction-rollers bearing upon the sliding head 6, the strap-loop 15 17 surrounding the stem 1, and fitted in a guideway in the head 6, the jaw-block 14 hinged in the strap-loop and adapted 75 to be turned to permit access to the inner surfaces and parts, and the spring interposed between the jaw-block and the stem 1, substantially as set forth.

3. In a pipe-wrench, the combination of the stem 1, having the head 2 with the teeth 5, of 85 the adjustable head 6 formed with a downwardly and outwardly inclined bearing and guiding surface, the antifriction-rollers resting upon said surface, the jaw-block 14 resting upon the said rollers and arranged to 90 travel on inclined lines to and from the stem, the sliding strap-loop having the part 17 surrounding the stem and the downwardly-inclined parts slidably mounted on the head 6 and carrying the jaw-block 14 having a series 95 of teeth 19 parallel to the inclined bearing-surface on the head 6 and to the series of rollers, substantially as set forth.

4. In a pipe-wrench, the combination with the shank, the fixed jaw, the sliding jaw, and the means for varying the distance between the fixed jaw and the sliding jaw, of means for automatically varying the travel of the sliding jaw toward and from the shank.

5. In a wrench, the combination of the 105 shank, the relatively fixed jaw, the head adjustable along the shank, the sliding jaw on the head, manually-operated devices for adjusting the head, and automatically-actuated devices for adjusting the travel of the sliding 110 jaw on the head while the head is being adjusted by the manually-operated adjusting devices, substantially as set forth.

6. In a wrench, the combination with the fixed jaw, the shank connected thereto, and a 115 tapered portion as at 28, a head 6 sliding along the shank, a sliding jaw 14, a holding and stopping device for the sliding jaw, adapted to engage with the tapered part of the shank and to hold the sliding jaw in different positions relatively to the shank, substantially as set forth.

In testimony whereof I affix my signature in presence of two witnesses.

JACOB W. KING
